United States Patent Office.

GEORGE H. SELLERS, OF PHOENIXVILLE, PENNSYLVANIA.

Letters Patent No. 83,553, dated October 27, 1868.

IMPROVEMENT IN HOT-WATER HEATERS.

The Schedule referred to in these Letters Patent and making part of the same.

To all whom it may concern:

Be it known that I, GEORGE H. SELLERS, of Phoenixville, in the county of Chester, and State of Pennsylvania, have invented certain new and useful Improvements in Hot-Water Heaters; and that the following is a full, clear, and exact description of the same, reference being had to the accompanying drawings, making part of this specification, in which—

Figure 1 represents a perspective view of the hot-water heater.

Figure 2 represents a vertical section through the same.

Similar letters of reference, where they occur, denote like parts of the heater in all the figures.

The object of my invention is to construct a hot-water heater, which will, by its form, produce a more direct action of the heat upon the walls of the water-chamber, at the same time causing the water to circulate more freely, and admitting the air to the fire-chamber in such a way as not to chill the fire-box nor cool the water, obviating, in this manner, the clinkering of the coal. I also obviate, in this heater, the necessity of float or stop-cock of any kind.

To enable others skilled in the art to make and use my invention, I will proceed to describe the same with reference to the drawings.

A represents the fire-chamber, which is made of a cylindro-conical form, so that the ascending heat will not only slide against, but will strike the walls *a* of the water-chamber C, transmitting to them all the heat contained in the whole current of ascending gases. This operation is accomplished, further, by means of the double conical damper B, which divides the current of hot gases, and directs it against the walls *a* of the water-chamber C. These inside walls *a* transmit the heat of the fire to the water, and being of a conical shape, permit the heated particles of water to leave the sides of this chamber as soon as heated to a greater degree than the surrounding particles.

The exterior, *b*, of the water-chamber is formed of two truncated cones, united at their greatest diameter. The cold water being admitted at *c*, strikes the fire-chamber A, at its hottest portion, in a thin sheet, allowing its rapid heating, while the upper cone concentrates the hot water to the discharging-pipes *d*. The sediment of the water can drop to the bottom in a space, *e*, the metal of the fire-chamber being there protected by the fire-brick lining D.

E is a circular fire-grate, supported and pivoted to the ash-box, G, in the usual manner.

H is the top of the heater, carrying a tube, *f*, through

which slides the rod *g* of the damper B. This top is half closed by a horizontal plate, *h*; the other half being closed by a door, *k*, revolving round the tube *f*, and operated by means of the knob *i*. Through the opening, closed by this door, *k*, is introduced the coal to feed the fire. The top, H, carries at right angles to it the exit-pipe *m*, through which the products of combustion escape to the chimney.

The air necessary for the combustion enters through the opening *n* in the ash-box, (which opening can be regulated by the sliding door *p*), and passes through the grate E to the fire. When the heated air and products of combustion gradually rise against the sides *a* of the water-chamber and transmit their heat to it, and consequently to the water, they then escape through the exit-pipe *m*. When it is desired to check entirely the draught in the furnace, the damper B is raised into the throat *q* of the fire-chamber, the charging-door *k* at the top is partially opened, admitting air direct into the smoke-pipe, without chilling the water or clinkering the fire.

The ash-box G and top H can be made either of sheet-iron or cast-iron, but it is preferred to construct the fire and water-chambers of wrought-iron, one-fourth of an inch thick, as it will stand a greater pressure than the city-mains, and can be connected directly to any of them, entirely avoiding any attention or feeding with water.

The damper B can be made hollow, and connected with a gas-pipe, in lieu of the rod *g*. This damper being perforated with small holes will introduce a current of heated air into the gases, and thus assist in consuming the products of combustion.

This heater has been found by experience to be a very simple, cheap, economical, and easy-managed water-heater.

Having thus fully described my invention, What I claim therein as new, and desire to secure by Letters Patent, is—

In combination with the external water-chamber C, the cylindro-conical fire-chamber A, as and for the purpose substantially as described.

I also claim, in a hot-water heater, the immediate connection of the water-chamber with the street-mains, so as to avoid the necessity of a reservoir, substantially as described.

GEO. H. SELLERS.
